UNITED STATES PATENT OFFICE.

JOHN HENRY CAIRNCROSS, OF TORONTO, CANADA, ASSIGNOR TO GEORGE F. BURTON, OF SAME PLACE.

ADVERTISING DEVICE.

SPECIFICATION forming part of Letters Patent No. 510,157, dated December 5, 1893.

Application filed December 24, 1892. Serial No. 456,284. (No model.)

To all whom it may concern:

Be it known that I, JOHN HENRY CAIRNCROSS, of the city of Toronto, in the county of York, in the Province of Ontario, Canada, 5 have invented a certain new and useful Improvement in Advertising Devices, of which the following is a specification.

The object of the invention is to provide a simple device by which advertising cards and 10 similar devices may be readily held in a conspicuous position and as easily removed and it consists in the peculiar construction, arrangement and combinations of parts hereinafter more particularly described and then 15 definitely claimed.

In the accompanying drawings—Figure 1, is a perspective inside view showing my device applied to the roof of a street car. Fig. 2, is an enlarged detail of the frame with a 20 portion of the molding in section. Fig. 3, is a sectional detail of the latch. Fig. 4, is a detail of the key for unlocking the latch. Figs. 5 and 6, are alternative forms of molding for holding the frame in position.

25 On the surface of the frame A, I print or otherwise place the advertising matter. On the one edge of the frame A, (preferably the bottom) I form a groove a, as shown in Fig. 2, a projection b, as shown in Fig. 5 or a clip 30 d, as shown in Fig. 6.

B, is a molding connected to the surface on which it is designed that the advertisement should be displayed. On this molding B, I form a beading C, when it is designed to engage with the groove a, or the clip d; or when 35 the projection b, is used on the frame A, I form a groove e in the molding B. This holds one end of the frame A. The other end fits against a molding D and in order to lock the 40 frame in position, I provide a spring latch E, either fixed to the frame A, as shown in Fig. 2, or connected to the molding D. In the

former case the latch will engage with a groove made in the molding D, as indicated in Fig. 2, or if the latch is connected to the 45 molding, it will engage with a groove made in the frame A.

In order to put the frame in position, the grooved end or its equivalent is placed on the molding B, and the other end of the frame 50 pushed in behind the molding D, the spring latch E, springing past the molding and locking the frame in position. The spring latch consists of the bolt g which is normally kept in the position shown by the spring k. It is 55 operated by a dog l which is secured to the key spindle i and which has two tails i which act on the lug g' projecting from the bolt.

I do not claim anything peculiar in the 5c spring latch or in the key F, but show them in the drawings as illustrating the practical way of accomplishing my purpose.

In order to prevent the frame A, rattling, I place steel springs L or pieces of rubber or other material in such a position as to hold 65 it steady.

What I claim as my invention is—

A frame for holding the advertising device and having a groove or projection formed on or connected to one edge and arranged to engage with a projection or groove formed on or connected to the surface on which the frame is placed, in combination with a spring latch arranged to lock the frame into its holding device, and a spring bearing on said frame 70 and surface whereby the frame is kept from rattling the whole being arranged substantially as and for the purpose specified. 75

Toronto, November 21, 1892.

JOHN HENRY CAIRNCROSS.

In presence of—

J. EDW. MAYBEE,
W. G. MCMILLAN.
